DEPTH CONTROL SYSTEM FOR TORPEDOES

Herbert L. Prescott, Sharon, Pa., assignor, by
mesne assignments, to the United States of
America as represented by the Secretary of the
Navy

Application March 8, 1946, Serial No. 653,188

3 Claims. (Cl. 114—25)

1

My invention relates to an electric system of control and more particularly to regulating means. My invention has general utility but to disclose its merits, I have shown my invention applied to the elevator rudders for a torpedo for controlling the depth of operation of the torpedo.

The Government of the United States has been granted a certain royalty-free license for governmental purposes with respect to the invention disclosed herein.

In the conventional depth control for a torpedo, as at present in use, a pendulum, mounted in the torpedo, closes a contact to energize either the up-rudder solenoid or the down rudder solenoid depending on the departure of the torpedo longitudinal axis from the normal aspect angle of the torpedo. In the normal desired operation of a torpedo, the torpedo progresses through the water with a slight nose-up position. In short, the desired operation requires that the longitudinal axis of the torpedo make a small up angle with the horizontal. This angle is designated the normal aspect angle of the torpedo and is considered the neutral position of the torpedo. The control effect of the depth control pendulum is thus made to be a function of the swing of the pendulum with reference to a plane normal to the neutral position.

The delays in the operation of the relays, solenoids, and mechanical components cause the torpedo to go considerably away from the neutral position before the elevators are actually operated, thus causing wide variations in pitch angle during the running of the torpedo.

One specific object of my invention is to produce anticipatory control effects on the elevators of a torpedo to thus decrease the variations in pitching angle of a torpedo.

A broad object of my invention is the provision of a periodic control effect angularly in advance by a selected angle to the cyclic variations of a physical quantity to thus substantially eliminate the cyclic variations of the physical quantity.

Another broad object of my invention is to provide for the substantial elimination of the periodic angular oscillation of a body by producing a counter force on the body of selected characteristics and having a like period but in angular advance by a selected angle.

Other objects and advantages will become more apparent from a study of the following specification and the accompanying drawing, in which:

Figure 1 is a diagrammatic showing of my system of control; and

Fig. 2 shows a curve of value in disclosing my invention.

2

The best understanding of my invention can probably be had from a study of the functions of the apparatus shown in Figure 1.

The instant the torpedo begins to accelerate toward the left at the moment the torpedo is launched, or fired from the firing tube, the pendulum P swings counterclockwise about the pivot X. This acceleration of the torpedo effects engagement between the movable contact 2 on the pendulum and the stationary contact 3. Almost at the same instant the torpedo movement causes the dog D on the firing tube to actuate the overcenter trigger switch T to operate to close the contacts 9 and 10. Since the trigger switch is provided with a sturdy spring S the overcenter movement of the trigger switch keeps the contacts 9 and 10 in engagement after operation of the switch.

The pendulum P is not only responsive, with reference to the torpedo, to the deflection of the longitudinal axis of the torpedo with reference to the horizon but also is responsive to the distance of the torpedo below the surface of the sea. To this end, the pressure-responsive means H, adjusted for a selected depth of operation, also acts on the pendulum.

The operations above mentioned establish a circuit from the positive terminal of the battery B through conductor 1, contacts 2 and 3, conductor 4, actuating coil 5 of the auxiliary down relay 6, conductors 7 and 8, and contacts 9 and 10 to the negative terminal of the battery. Operation of relay 6 establishes a circuit from conductor 1 through conductor 11, contacts 12, now closed, actuating coil 13 of the elevator rudder control relay 14, and conductor 15 to the negatively energized conductor 8.

Operation of the elevator control relay establishes a circuit from conductor 1, through conductor 16, contacts 17, now closed, the down rudder solenoid coil 18 and conductor 19 to conductor 8. The armature 20 is thus moved toward the left and the yoke 21 for the elevator rudders is moved clockwise to move the elevators 22 down, or clockwise. The torpedo, therefore, immediately starts down on firing. As soon as the torpedo is beyond the propulsive effect of the firing tube, the acceleration toward the left ceases and the normal operation of the depth control takes effect.

As the nose of the torpedo, as just explained, starts down and the acceleration toward the left ceases, the pendulum begins to swing clockwise. The initial operation is to open the circuit at contacts 2 and 3.

The auxiliary down relay 6 is thus deenergized

and contacts 12 are opened. The down elevator or rudder control relay 14 is deenergized opening contacts 17 but closing contacts 24. The closing of contacts 24 establishes a circuit from conductor 1 through conductor 23, contacts 24, the up-rudder solenoid 25 to the conductor 8.

It will be noted that the up-rudder solenoid is energized by the interruption of the circuit at contacts 2 and 3. Movement of the elevators to an up-rudder position thus occurs before the pendulum P has even reached its neutral, or mid-position. A phase advance is thus produced on the rudders ahead of the pendulum position.

It is apparent that the inertia of the torpedo body is such that the nose will continue down even though the rudders are in the up-rudder position. The pendulum thus moves to close contacts 2 and 33 whereupon a circuit is established from the energized contact 33 through the actuating coil 26 of the auxiliary up relay 27 to energized conductor 8.

Operation of relay 27 closes contacts 28 to establish a circuit from conductor 1 through contacts 28, actuating coil 29 of the sequence control relay 30 and contacts 31, now closed, to conductor 8. This relay closes contact 32 and thus the relay holds itself in.

As the torpedo is being moved from the maximum nose-down position in the direction of a nose-up position but before the torpedo has even attained a horizontal position the circuit at contacts 2 and 33 is interrupted. The auxiliary up relay 27 is deenergized to open contacts 28 and to close contacts 34. Since relay 30 is energized contacts 35 are closed. The consequence is that the rudder control relay 14 is energized to effect the deenergization of the up-rudder solenoid 25 and the energization of the down-rudder solenoid 18.

From this action, it will be apparent that while the torpedo is still in a nose-down position but swinging to an up-nose position, the rudders 22 are moved to a down-rudder position by a certain phase angle in advance of the torpedo movement. As the torpedo swings to an up-nose position, contacts 2 and 3 are closed. This operation closes the circuit for the auxiliary down relay 6. This relay closes contacts 12 to thus maintain the rudder control relay energized independent of contacts 34 and 35. The elevators thus remain in the down-rudder position while the torpedo completes its swing to its maximum up-nose position.

The effect of the elevators will, of course, be to swing the torpedo back from its maximum nose-up position toward a horizontal position.

When the relay 6, in the last operation of this relay above discussed, closed contacts 12, it also opened contacts 31. This latter operation deenergizes the sequence control relay 30 with the result that contacts 35 are opened. This opening of the contact 35 does not at the moment it does occur affect the operation of the rudder control relay 14 but when the torpedo makes a given relatively small up-nose angle with the horizontal during its swing from up-nose angle to a horizontal position the circuit at contacts 2 and 3 is interrupted. The auxiliary down relay 6 is thus deenergized. In consequence, the rudder control relay 14 is deenergized effecting the energization of solenoid 25.

Again the elevators are moved to an up position in angular advance to the movement of the torpedo. The cycle thus repeats itself during the periodic movement of the torpedo. The movement may become even clearer from a study of

Fig. 2 where the curve 36 represents the periodic swing of the torpedo with reference to its horizontal, or neutral, position.

At the moment of firing of the torpedo the elevators have a down-rudder position for a short time t_1 . While the torpedo gains depth and has a nose-down position, the elevators have an up position for time t_2 . For time t_3 the elevators have a down position although the torpedo nose is down but swinging to an up position. For time t_4 the elevators remain down, while the torpedo swings from a nose-down position to the maximum nose-up position and begins to swing to a nose-down position. During the time intervals t_5 , t_6 and t_7 , the elevators are up, but t_5 represents the advance phase angle.

The diagram of Fig. 2 thus shows that the rudder operations occur before the neutral position is reached, thus providing a phase advance to compensate for the inertia of the body being controlled and the time delay of the operating elements.

To obtain the least possible oscillation, the settings of the high and low contacts of the pendulum should be just under the minimum range required for the torpedo body to respond to the rudders as determined by the inertia of the body and the size and throw of the rudders.

The principle of operation herein disclosed, that is, the use of contacts operated by one extremity of a variable quantity to start corrective measures to limit the magnitude of the opposite extremity of that quantity, is applicable not only to torpedo depth control but to any regularly varying quantity where the time constant of the variable quantity is greater than the time constant of the control mechanism.

From the foregoing it is thus apparent that I provide a damping effect to swings of the torpedo that goes into action while the torpedo is moving in a given direction before having attained a neutral position. The oscillations of the torpedo are thus reduced to a minimum.

It is thus apparent that my invention is not limited to the particular showing made but is to be limited only by the scope of the claims here-to appended.

I claim as my invention:

1. In a system of control, in combination, a conveyance traveling at a given rate through a fluid medium, elevator rudders on said conveyance for controlling the travel of said conveyance with reference to a horizontal plane, the normal tendency of said conveyance is to oscillate periodically angularly in a vertical plane, a pendulum on said conveyance disposed to remain fixed vertically while said conveyance oscillates, a source of electric energy on said conveyance, switching means held in closed position by said pendulum for all angles of declination of the conveyance greater than a given relatively small angle of declination, an electromagnetic device energized by said switching means when in closed position, first electromagnetic means for actuating said elevator rudders to the up-rudder position, second electromagnetic means for actuating said elevator rudders to the down rudder position, an elevator control relay including a first switch normally closed when said relay is deenergized to energize the first electromagnetic means, and including a second switch operable to closed position by the energization of said relay to thus effect the energization of said second electromagnetic means, 75 and contact means operable by said electromag-

netic device for energizing said relay upon movement of the conveyance from some relatively great angle of declination to an angle of declination less than said given relatively small angle of declination.

2. In a system of control for a torpedo, in combination, a torpedo in normal use propelled through the sea at a given speed and depth but which torpedo normally swings angularly in a vertical plane, that is, pitches above the horizontal and below the horizontal through angles of elevation and angles of declination, elevator rudders for the torpedo, a pendulum mounted in the torpedo and adapted to remain vertically so that the angle the pendulum makes at any instant with torpedo axis is a measure of the angles of elevation and angles of declination, a source of electric energy in said torpedo, switching means including one pair of contacts held closed by the pendulum for all angles of declination greater than a given relatively small angle of declination, an electromagnetic device energized from said source when said one pair of contacts are closed, first electromagnetic means for actuating said elevator rudders to up-rudder position, a second electromagnetic device energized from said source when said other pair of contacts are closed, second electromagnetic means for actuating said elevator rudders to down-rudder position, an elevator control relay including a first switch normally closed when said relay is deenergized to energize the first electromagnetic means, and including a second switch operable to closed position by the energization of said relay to thus effect the energization of said second electromagnetic means, and first contact means operable by said electromagnetic device for energizing said relay upon movement of the torpedo from some relatively great angle of declination less than said given relatively small angle of declination.

3. In a system of control for a torpedo, in combination, a torpedo in normal use propelled through the sea at a given speed and depth but which torpedo normally swings angularly in a vertical plane, that is, pitches above the horizontal and below the horizontal through angles of elevation and angles of declination, elevator rudders for the torpedo, a pendulum mounted in the torpedo and adapted to remain vertically so that the angle the pendulum makes at any instant with torpedo axis is a measure of the angles of elevation and angles of declination, a source of electric energy in said torpedo, switching means including one pair of contacts held

closed by the pendulum for all angles of declination greater than a given relatively small angle of declination and including another pair of contacts held closed by the pendulum for all angles of elevation greater than a given relatively small angle of elevation, an electromagnetic device energized from said source when said one pair of contacts are closed, first electromagnetic means for actuating said elevator rudders to up-rudder position, a second electromagnetic device energized from said source when said other pair of contacts are closed, second electromagnetic means for actuating said elevator rudders to down-rudder position, an elevator control relay including a first switch normally closed when said relay is deenergized to energize the first electromagnetic means, and including a second switch operable to closed position by the energization of said relay to thus effect the energization of said second electromagnetic means, contact means operable by said first electromagnetic device for energizing said relay upon movement of the torpedo from some relatively great angle of declination to an angle of declination less than said given relatively small angle of declination and contact means operable by said second electromagnetic device for energizing said relay upon movement of the torpedo from some relatively great angle of elevation to an angle of elevation less than said given relatively small angle of elevation.
